UNITED STATES PATENT OFFICE.

ANALDO M. ENGLISH, OF BROOKLINE, MASSACHUSETTS, ASSIGNOR TO CUMMINGS MACHINE WORKS, OF BOSTON, MASSACHUSETTS, A CORPORATION OF MASSACHUSETTS.

SEWING-MACHINE ATTACHMENT FOR SPIRAL STITCHING.

Application filed February 26, 1921. Serial No. 447,912.

To all whom it may concern:

Be it known that I, ANALDO M. ENGLISH, a citizen of the United States, residing at Brookline, in the county of Norfolk, State 5 of Massachusetts, have invented a certain new and useful Improvement in Sewing-Machine Attachments for Spiral Stitching, of which the following is a specification, reference being had therein to the accompanying drawings.

The invention provides means of novel and improved character and construction adapted especially for use in stitching spirally, as for instance in connection with the 15 brims of middy caps, after the cloth composing the same has been made up into the shape of slightly flaring endless bands.

The said means consists in devices comprising a cloth-guide and means actuated 20 through the reciprocating movement of the sewing machine needle-bar to give a progressive lateral movement to the said cloth-guide to cause the stitches made by the machine to form a spiral course. It consists, further, in means of novel construction for actuating a cloth-guide to cause lateral traverse thereof for the purpose noted. It consists, further, in a laterally-traversing edge-guide having means as specified 25 hereinafter acting automatically to keep one edge of the cloth in proper contact with the edge-guide.

The drawings show an illustrative embodiment of the general invention and the 30 features just referred to, in the shape of an attachment designed for removable and adjustable application to a sewing machine.

Fig. 1 of the drawings is a perspective view of a sewing machine having the said 35 embodiment applied thereto.

Fig. 2, Sheet 2, is a front elevation of the said machine and embodiment.

Fig. 3, Sheet 2, is a plan view of the attachment, showing the needle-bar in horizontal section on line 3, 3, of Fig. 2.

Fig. 4, Sheet 1, is a view on a relatively enlarged scale showing certain parts at the left of line 4, 4, of each of Figs. 2 and 3.

Fig. 5, Sheet 3, is an end elevation of 50 the machine and attachment.

Figs. 6, 7, 8, and 9, Sheet 3, are views on relatively enlarged scale, Fig. 6 being a partly sectional plan view of a portion of the guide-traversing means; Fig. 7 being

a view mainly in vertical section in the 55 plane of line 7, 7, in Fig. 8; Fig. 8 being a view mainly in vertical section in the plane of line 8, 8, in Fig. 7; and Fig. 9 being a detail view partly in vertical section on line 9, 9, of Fig. 7.

Referring to the drawings,—

The cloth-guide 1 of the illustrated embodiment of the invention is an edge-guide for the endless band made up for the brim of a middy-cap; 1^a is its cloth-guiding surface. The said edge-guide is located at the right of the needle-bar 2 and needle 3 (Fig. 5), in the required working relation to the needle-bar and needle. In this instance it is connected by a pivot 1^b (Figs. 3 and 4) 70 with an arm 5 extending rearwardly from a rod or spindle 6 located at the front of the machine and extending toward the right and there connecting with the traverse mechanism. The traverse mechanism operates to move rod or spindle 6 lengthwise, and thereby the edge-guide is traversed sidewise relative to the needle. The rod or spindle 6 is capable of turning around its longitudinal axis so as to permit the arm 5 and edge-guide to swing down toward the work-plate, or to be moved upwardly therefrom, and the pivotal connection of the edge-guide with the arm 5 at 1^b enables the edge-guide to adjust itself 85 to the surface of the work-plate. This is a preferred mode of combining the edge-guide with its operating connections, but in some cases the edge-guide may otherwise be mounted or combined with the rod or 90 spindle. The edge-guide may rest by gravity upon the surface of the work-plate, but preferably a spring is employed to keep it down in place. In the present instance a bent flat spring 5^a attached to arm 5 contacts with the under side of an abutment 95 finger 12 projecting from frame π of the attachment, and its tension bears arm 5 and the edge-guide downward. As the edge-guide is traversed laterally the spring slides 100 along the finger 12, remaining in engagement therewith.

The means by which the cloth, in being advanced to the needle, is diverted or deflected laterally toward the guiding surface of the 105 edge-guide 1, so as to ensure that the edge of the cloth shall be in contact with such surface, is in this instance a roll 8 that is

employed as a presser. The cloth is passed between the roll 8 and the surface of the work-plate. The said roll has its longitudinal axis at an angle to the said surface, whereby the tendency to divert or deflect the cloth laterally is secured. As shown, it is of circumferentially grooved and ribbed construction, for more effective engagement with the cloth and greater effect in controlling the latter. The grooving, etc., is spiral in the present instance, but may be annular. Other forms or constructions of laterally-diverting or deflecting means may be combined with the edge-guide in some instances.

15 A pin 81 extending horizontally outward from the edge-guide at the rear of the needle-bar and needle is adapted to hold the cloth from rising as it moves rearward through the machine.

20 In order that the roll 8 shall participate in the traversing movements of the edge-guide 1, and continue in the same working relations therewith, the roll is connected with the edge-guide, through being carried by the 25 forward end of the edge-guide. For the purpose of enabling it to act as a presser it is mounted with capacity for vertical movement. In this instance the roll is fitted upon a stud or pin 9 that is disposed at the angle 30 aforesaid with respect to the cloth-guiding surface of the edge-guide, and that projects inwardly toward the edge-guide from an arm 10 of a swing-frame having its hub or sleeve 10^a fitted upon a stud or pin 10^b carried by the forward portion of the edge-guide. This supporting pin or stud 10^b is arranged at the same inclination with respect to the cloth-guiding surface of the edge-guide as the axis of the roll, the two 35 studs or pins being parallel with each other.

40 Gravity alone may be depended upon to cause the roll to bear upon the top surface of the cloth, but preferably I combine with the swing-frame a suitable spring to act to 45 ensure the proper amount of pressure. In this instance a flexure spring 11 is affixed by one end to the arm 10 of the swing-frame and arranged to engage by its other end with the fixed abutment finger 12, projecting 50 as aforesaid from the attachment-frame α so that the reaction of the spring from the said abutment finger bears the swing-frame and roll downward toward the work-plate.

55 The means for traversing the edge-guide includes a traverse-screw 16 which is hollow and surrounds a portion of the length of the rod or spindle 6 between two guides 6^a, 6^b, in connection with attachment-frame α , in 60 which the rod or spindle is mounted. The two guides prevent endwise movement of the screw. For communicating endwise movement to rod or spindle 6 from the traverse-screw a block or collar 6^c fixed upon 65 the outer end of the rod or spindle has at-

tached thereto a flat spring-strip 6^d carrying a nut-segment 17 which engages the threaded portion of the screw, so that in consequence of the turning of the screw the rod or spindle is advanced lengthwise 70 through the guides 6^a, 6^b, and the interior of the screw, and thereby the edge-guide is traversed. A knob or handle 6^e is provided upon the spring-strip 6^d, for convenience in disengaging the nut-segment from the screw and shifting the edge-guide by hand, either in placing the edge-guide in starting position or for purposes of adjustment. An unthreaded space 6^f of reduced diameter is left at the outer end of the body of the traverse-screw to avoid injury such as would result from continuing the traversing movement too far. Such clear space safeguards against the nut-segment being forced against the guide 6^b.

80 In this embodiment of the invention, for the actuation of the traverse means through the reciprocating movements of the needle-bar, an arm 13 is employed. The said arm is engaged by one end thereof with a projection 14 (Figs. 3 and 4) from a block 15 carried by the needle-bar and made fast thereon by a clamping screw 15^a, this arm being mounted upon the attachment-frame α by means of a pivotal stud 13^a projecting from the stud and fitted in a bearing α' upon the attachment-frame, so that the arm is swung up and down vertically as the needle-bar and needle rise and fall. This vertically-swinging movement of the arm is utilized to impart a gradual turning movement to the traverse-screw 16.

90 The means through which the swinging-arm 13 transmits movements to the screw 16, to turn the latter, is an intermittent clutch arrangement comprising, in the case of this embodiment, a link 18, (shown separately in Fig. 9, Sheet 3,) a swinging carrier 19, clutch-dogs 20, 20, (Figs. 7 and 8,) and a disk 21 attached to the said screw. The swinging carrier 19, as illustrated in Figs. 6, 7, and 8, is a slotted arm embracing the disk and hung by half-bearings at one end thereof upon plain unthreaded portions of the sleeve of the screw. The clutch-dogs 20, 20, are balls located at opposite sides of the disk, between the latter and downwardly converging inclined surfaces which in this instance are opposite portions of the wall of a downwardly tapering vertical chamber at the closed end of the slot in the swinging carrier. Normally the balls are held down with yielding force by means of presser-bars 20^a, 20^b, that rest by their lower ends upon the tops of the balls, the upper portions of the said presser-bars being encircled by expanding spiral springs 20^b, 20^b, that are confined between shoulders on the presser-bars and the top of an arch-shaped piece 21^a rising from the carrier. The up-

per ends of the presser-bars extend upward through holes in said arch-shaped piece. The link 18 has upper and lower slots or recesses in which blocks 22, 23, are mounted 5 by means of transverse pivots 22^a, 23^a. A stud 18^b projecting from one side of swinging arm 13 enters a hole in the upper block 22, and a stud 19^b projecting from the outer end of the carrier enters a hole in the lower 10 block 23. In consequence of the connection between the arm 13 and the carrier established by means of the link, the swinging movements of the arm produce swinging of the carrier. The blocks 22, 23, swing upon 15 their respective pivotal connections 22^a, 23^a, with the body of the link, so as thereby to compensate for the fact that the arm 13 and the carrier 19 swing around axes that are disposed at right angles with each other. 20 As the carrier swings upward, the action of the converging wall of the ball-containing chamber upon the balls presses the latter inward against the opposite sides of the disk, so as to cause them to grip the disk and 25 cause the latter and the screw 16 to turn during the continued upward movement of the carrier. In the downward movement of the carrier the upward flare of the said wall causes the binding action of the balls upon 30 the disk to be relieved, and hence the carrier returns downward without turning the disk and screw backward. Backward turning is provided against, in addition, by means of a frictional holding device or clamp carried 35 by attachment-frame α and comprising opposite yielding arms 24, 24, having contact-portions 24^a, 24^a, (Fig. 6) which bear against opposite surfaces of the disk. Said arms are pressed with yielding force toward 40 each other by means of an expanding spiral spring 25 (Fig. 6) confined under the cup-shaped head of a nut 26 fitted to a screw-threaded stud 27 projecting from one arm through a hole in the other, said spring taking 45 bearing against the outer side of the latter arm. The sleeve-like central body of the said nut also occupies the said hole in the second arm. Adjustment of the nut upon the stud regulates the tension of the spring 50 and the frictional effect of the clamp.

The rate at which the edge-guide is traversed sidewise is varied by regulating the extent of the return movement of the balls in the downward stroke of the carrier. This 55 is accomplished by endwise adjustment of a pin 28 having the upper portion thereof slotted or forked and arranged so as to embrace the disk adjacent the balls, below the latter. The return stroke of the carrier 60 carries the balls into contact with the ends of the limbs or branches of the pin, so that said ends stop the balls in their return movement, and thus the position of the ends determines the position from which the balls 65 start in reengaging with the disk and act-

ing to rotate the same. The endwise adjustment of the pin 28 is provided for in this instance by means of an adjustment-screw 29 having a tapering or cone-shaped portion 29^a that acts against the lower end 70 of pin 28. By turning the adjustment-screw 29 within the screw-threaded hole in attachment-frame α which it occupies, the adjustment-screw is advanced or retracted, as the case may be, to effect the shift of pin 28 that 75 is necessary for the required regulation of the rate at which the traverse-screw is rotated.

The attachment-frame α is bored to fit upon the post y rising from the attachment-stand y' which is mounted upon the base-plate B of the sewing machine and made fast to the latter by means of a clamping screw y^2 and washer y^3 . The stem of the clamping screw occupies a slot y^4 (Fig. 1) in the base-plate, 80 such slot providing for transverse adjustment of the attachment with reference to the parts of the sewing machine. Thereby the attachment is detachably and adjustably secured in place in a sewing machine. The 85 attachment-frame α is adjustable vertically upon post y , and is secured by means of a clamping screw y^2 at the proper height to suit that of the upper surface of the work-plate, and the adjacent parts of the machine. By constructing the organization as 90 an attachment it is made applicable to and removable from an ordinary sewing machine at will. So also in case any part of the organization should get out of order, the organization as a whole may be removed bodily from the sewing machine with which it 95 has been combined, and replaced by another like organization, so that the use of the machine may continue without any material interruption.

In the case of the illustrated embodiment of the invention the construction of the sewing machine is not affected, and the addition thereto of worms or screws, special gearing, 100 etc., for the actuation of the traverse mechanism is avoided. All that is required is to apply the attachment to the machine, adjust its parts in proper working relation with the machine proper, apply the block 15 to the 105 needle-bar and fasten it in place by means of its clamping screw 15^a, and engage arm 13 of the attachment with projection 14 of the block.

The disk 21 of the intermittent-clutch 110 devices is made thin and light, so that there is practically no liability to overrunning of the same and the traverse-screw. The employment of two clutch-balls located at opposite sides of the disk secures a well-balanced 115 action, free from tendency to cramping.

What is claimed as the invention is,

1. A sewing machine attachment for spiral stitching comprising a cloth-guide and means adapted to be actuated through 120

130

2. Devices for spiral stitching comprising an edge-guide, means connected therewith arranged to act upon the upper surface of the cloth and by engagement with such surface deflect the cloth toward the edge-guide so as to keep the edge of the cloth in contact with said guide, and means for traversing the edge-guide and said deflecting means transversely to produce a spiral course of 15 stitches.
3. The combination comprising an edge-guide, a presser-roll connected therewith constructed and arranged to act upon the upper surface of the cloth to deflect the 20 cloth toward the edge-guide so as to keep its edge in contact with the said guide, and means for progressively traversing the edge-guide and presser-roll transversely.
4. The combination comprising an edge-guide, a circumferentially grooved roll connected therewith which deflects the cloth toward the edge-guide and tends to keep its edge in contact with the guide, and means for progressively traversing the edge-guide 25 and roll transversely.
5. The combination comprising an edge-guide, a presser-roll, a vertically-movable carrier therefor connected with said edge-guide, and means for progressively traversing said parts in unison transversely.
6. The combination comprising an edge-guide, a vertically-movable carrier connected therewith, a presser-and-deflector roll mounted in said carrier operating to deflect 40 the cloth laterally against the edge-guide, and means for progressively traversing said edge-guide transversely.
7. The combination comprising an edge-guide, a vertically-movable carrier connected therewith, a presser-and-deflector roll mounted in said carrier with its axis of revolution inclined with respect to said edge-guide, to deflect the cloth laterally against the latter, and means for progressively traversing said edge-guide transversely.
8. The combination comprising an edge-guide, a vertically-movable carrier connected therewith, a circumferentially grooved presser-and-deflector roll mounted in said carrier with its axis of revolution inclined with respect to said edge-guide, to deflect the cloth laterally against the latter, and means for progressively traversing said edge-guide transversely.
9. Devices for spiral stitching comprising a cloth-guide, means for progressively traversing said cloth-guide transversely, and operating devices for such means, adapted to be intermittently actuated through the 65 movement of a sewing-machine needle-bar.
10. Devices for spiral stitching comprising a cloth-guide, means for progressively traversing said cloth-guide transversely, and intermittent-clutch operating devices for such means, adapted to be actuated through the movement of a sewing-machine needle-bar.
11. Devices for spiral stitching comprising a cloth-guide, a traverse-screw operatively combined therewith, and intermittent-clutch operating devices for the said screw adapted to be actuated through the movement of a sewing machine needle-bar.
12. Devices for spiral stitching comprising a cloth-guide, traverse-means operatively combined therewith, a disk in connection with said traverse-means, clutch-dogs opposing each other at opposite sides of the said disk, and means for reciprocating said dogs, adapted to be actuated from a part 80 of a sewing machine.
13. Devices for spiral stitching comprising a cloth-guide, traverse-means operatively combined therewith, a disk in connection with said traverse-means, clutch-dogs opposing each other at opposite sides of the said disk, and means for reciprocating said dogs, adapted to be actuated through the movement of a sewing machine needle-bar.
14. Devices for spiral stitching comprising a cloth-guide, traverse-means operatively combined therewith, a disk in connection with said traverse-means, dogs opposing each other at opposite sides of the said disk, a dog-carrier having a dog-containing 90 chamber with converging wall, and means for actuating said dog-carrier from a moving part of a sewing machine.
15. Devices for spiral stitching comprising a cloth-guide, traverse-means operatively combined therewith, a disk in connection with said traverse-means, dogs opposing each other at opposite sides of said disk, a dog-carrier having a dog-containing chamber with converging wall, means for actuating said dog-carrier from a moving part of a sewing machine, and means for limiting the return stroke of the dogs, adjustable to vary the speed of lateral traverse of the cloth-guide.
16. Devices for spiral stitching comprising a cloth-guide, traverse-means operatively combined therewith, a disk in connection with the said traverse-means, dogs opposing each other at opposite sides of said disk, a dog-carrier having a dog-containing chamber with converging wall, means for actuating said dog-carrier from a moving part of a sewing machine, a divided stop working at opposite sides of said disk for limiting the return stroke of the dogs and fixing the starting point thereof, and means for adjusting the said stop to vary the action in turning the said disk and the rate 120 of traverse.

17. Devices for spiral stitching comprising a cloth-guide, a rod or spindle extending therefrom, a hollow traverse-screw through which said rod or spindle extends constituting a guide for the rod or spindle, and adapted to be actuated from the mechanism of a sewing machine, and a nut-member through which the traverse-screw imparts movement to the rod or spindle and cloth-guide.

18. Devices for spiral stitching comprising a hollow traverse-screw adapted to be actuated from the mechanism of a sewing machine, a rod or spindle actuated by said hollow screw, extending axially therethrough, and having an arm extending at an angle from it adjacent the stitch-making point in a sewing machine, and an edge-guide pivotally hung to said arm and

adapted to conform to the surface of the 20 sewing machine work-plate.

19. Devices for spiral stitching comprising an edge-guide, a presser connected therewith which bears upon the upper surface of the cloth and by engagement with such surface operates to deflect the cloth toward the edge-guide so as to keep the edge of the cloth in contact with said guide, and means for traversing the edge-guide and said deflecting means transversely to produce a spiral course of stitches.

In testimony whereof I affix my signature in presence of two witnesses.
